US00D805133S

(12) **United States Design Patent** (10) **Patent No.:** **US D805,133 S**
(45) **Date of Patent:** **** Dec. 12, 2017**

(54) **ELECTRONIC CONSOLE FOR GAMING AND/OR ENTERTAINMENT PURPOSES**

(71) Applicant: **Microsoft Corporation**, Redmond, WA (US)

(72) Inventors: **Bryan A. Sparks**, Sammamish, WA (US); **Nicolas Denhez**, Seattle, WA (US); **YeongKyu Yoo**, Bellevue, WA (US); **Andrew Kim**, Bellevue, WA (US); **Young Duk Song**, Kirkland, WA (US); **Gregory G. Jones**, Seattle, WA (US); **Carl J. Ledbetter**, Mercer Island, WA (US)

(73) Assignee: **Microsoft Corporation**, Redmond, WA (US)

(**) Term: **15 Years**

(21) Appl. No.: **29/564,527**

(22) Filed: **May 13, 2016**

(51) LOC (10) Cl. **21-01**

(52) U.S. Cl.

USPC **D21/332**

(57) **CLAIM**

The ornamental design for an electronic console for gaming and/or entertainment purposes, as shown and described.

DESCRIPTION

FIG. 1 is a front perspective view of an electronic console for gaming and/or entertainment purposes showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing of the various unshaded elements of the electronic console in FIGS. 1-7 is for environmental purposes only and forms no part of the claimed design.

1 Claim, 7 Drawing Sheets
